UNITED STATES PATENT OFFICE.

HORACE PFOUTS GORMAN, OF HAZLETON, PENNSYLVANIA.

LIQUID-DISPENSING APPARATUS.

977,298.

Specification of Letters Patent. Patented Nov. 29, 1910.

Application filed December 2, 1908. Serial No. 465,671.

To all whom it may concern:

Be it known that I, HORACE PFOUTS GORMAN, a citizen of the United States, residing at Hazleton, in the county of Luzerne and State of Pennsylvania, have invented a new and useful Liquid-Dispensing Apparatus, of which the following is a specification.

This invention relates to apparatus for dispensing liquid and is especially designed for use in connection with soda fountains and the like for dispensing syrups, although it is equally useful wherever it is desired to dispense liquid in predetermined quantities.

The object of the invention is to provide a simple device of this character which can be readily connected to any form of table or other supporting structure and which dispenses with the use of valves for controlling the discharge of liquid, there being no parts of the device which are likely to get out of order as a result of long continued use.

A further object is to provide a liquid dispensing device which is bodily movable for the purpose of discharging a predetermined quantity of liquid therefrom, the flow of the liquid from the device being controlled by atmospheric pressure.

A still further object is to provide means whereby the device can be readily adjusted to increase or diminish the quantity of liquid dispensed at one operation.

With these and other objects in view the invention consists of certain novel details of construction and combinations of parts hereinafter more fully described and pointed out in the claims.

In the accompanying drawings the preferred form of the invention has been shown.

In said drawings:—Figure 1 is a central vertical section through the complete apparatus and showing the container in its normal position. Fig. 2 is a plan view of the apparatus. Fig. 3 is a front elevation thereof, the lower portion of the supporting standard being broken away. Fig. 4 is a central vertical section through a portion of the container and showing one of the positions assumed thereby while it is being swung backwardly for the purpose of discharging liquid.

Referring to the figures by characters of reference 1 designates a standard having a yoke 2 at its lower end designed to engage the edge of a table, counter or other supporting structure, said yoke being provided with

a clamping device such as a screw 3 whereby the standard can be firmly secured to the supporting structure. Ears 4 are struck outwardly from the edges of standard 1 near its upper end and constitute side guards for a U-shaped extension 5 formed integral with the middle portion of a yoke 6, said yoke being disposed in a plane perpendicular to the plane occupied by the U-shaped portion 5. A clamping plate 7 bears upon the extension 5 and between the ears 4 and is held in place by means of a bolt 8 slidably mounted within a slot 9 extending longitudinally within the standard, there being any suitable means such as a wing nut 10 for the purpose of binding the parts firmly together. The terminals of the yoke 6 are inturned as indicated at 11 to form alining trunnions, and connecting the sides of the yoke and adjacent the standard 1 is a stop strip 12 which is bowed downwardly and provided at its central portion with a cushion 13 formed of rubber tubing or any other suitable soft material. A guide ear 14 extends at right angles from the upper end of the standard 1 and has spaced openings 15 therein in which are slidably mounted the parallel arms of an elongated loop 16 which loop extends downwardly and is provided at its lowermost portion with a forwardly extending arch 17 extending under the stop strip 12 and provided with a cushioning device 18 of rubber or other suitable material as clearly indicated in Fig. 1. A clamping plate 19 bears upon the arms of loop 16 close to the guide ear 14 and is engaged by a bolt 20 extending through the standard 1 and the loop 16, any suitable means, such as a wing-nut 21, being provided for clamping the parts firmly together.

The container portion of the present apparatus consists of a preferably cylindrical receptacle 22 formed of glass, although it is to be understood that if preferred the same can be made of any other suitable material, and provided, if desired, with a transparent panel whereby the contents of the receptacle can be readily seen at all times. The lower portion of the receptacle is screw-threaded as indicated at 23 and is designed to be detachably engaged by a screw-threaded flange 24 extending from the margin of a base plate 25. A disk-like partition 26 is interposed between the open end or bottom of the

receptacle 22 and the plate 25 and is spaced any desired distance from said plate 25 and from the open bottom of the receptacle by means of spacing rings or washers 27. An outlet opening 28 is formed in the front portion of the partition 26, and another outlet opening 29 is formed in the rear portion of the base plate 25. An outlet tube 30, preferably angular in cross section, extends diametrically along the bottom face of the plate 25 and from front to rear thereof, the rear end of the outlet tube being extended upwardly and longitudinally of the flange 24 as indicated at 31, while the front end of the tube is inclined upwardly relative to the base plate 25 as shown at 32, the upper end of the inclined portion terminating in a downwardly directed outlet spout 33. The outlet of this spout is disposed in a plane parallel with, but extending above, the partition 26. The upper or open end of the rear extension 31 of the tube is located above the highest portion of the partition 26. The tube 30 is preferably formed angular in cross section so as to have considerable capacity without extending any undesirable distance below the base plate 25.

A band 34 extends around the upper portion of the receptacle 22 and has its ends 35 extended rearwardly as indicated at 35 and secured together in any preferred manner, said ends forming an arm which is located above the stop strip 12 and designed to swing downwardly thereonto to maintain the receptacle normally in a predetermined position. Enlargements 36 are formed on the band adjacent the sides of the receptacle and have sockets 37 therein for the reception of the inturned ends 11 of the yoke 6. These enlargements and sockets are located slightly in front of the center of the receptacle so that the weight of the lower portion of said receptacle and the parts connected thereto will be sufficient to maintain said receptacle normally in the position indicated in Fig. 1 and with the end portion 35 of the strap 34 bearing on the cushion 13.

A retaining loop 38 extends upwardly from the base plate 25 and through the opening 28, said loop being detachably engaged by a hook 39 formed upon the bottom 40 of an interior receptacle 41. This interior receptacle is preferably cylindrical in form and the bottom 40 is designed to screw thereonto to close the same. A spacing frame 42 is secured upon the top of the inner receptacle and is preferably triangular in form, the apices or angles of the frame being disposed to bear against the wall of the receptacle 22 so as to hold the inner receptacle 41 constantly concentric with the outer receptacle.

A push plate 43 extends downwardly from the front portion of the base plate 25 and is for the purpose hereinafter set forth.

When it is desired to use the apparatus hereinabove described the arms 6 are sprung laterally so as to remove the ends 11 thereof from the sockets 37. The receptacle 22 and the parts connected thereto should then be inverted, after which the flange 24 of the base plate 25 may be unscrewed from the receptacle 22 and lifted from position on the receptacle. The interlocking loop 38 and hook 39 will prevent the inner compartment 41 from dropping within the inverted receptacle 22 and will also cause said inner receptacle to lift out of the receptacle 22 when the base plate 25 is removed. The liquid to be dispensed is placed within the inverted receptacle 22, ice or other suitable refrigerating material is placed within the inner receptacle 41, and said inner receptacle is then closed and its hook 39 placed in engagement with the loop 38. The parts are then reassembled, after which the receptacle 22 is returned to its normal position with the bottom plate 25 and tube 30 lowermost and the ends 11 of yoke 6 are sprung into the sockets 37. The said receptacle will thus be supported in the position shown in Fig. 1, with the ends 35 of strap 34 bearing on the stop strip cushion 13. When the parts are thus located a portion of the liquid contents of receptacle 22 will flow downward through the opening 28 and into the compartment 44 formed between the base plate 25 and partition 26. It will then flow into the tube 30 through the opening 29 until the level of the liquid within the tube reaches the level of the highest portion of the opening 28, whereupon the atmospheric pressure upon the liquid contained within the tube will operate to prevent further downward flow of the liquid and said liquid will there remain as indicated in Fig. 1. When it is desired to remove a predetermined quantity of liquid from the apparatus, the glass or other receptacle for receiving the liquid is pressed against the push plate 43 so as to cause receptacle 22 and the parts connected thereto to swing bodily backward toward the standard 1. The level of the liquid will thus be shifted and the outlet 33 will be swung downward into position in a horizontal plane extending close to but slightly above the highest portion of the outlet opening 28. A portion of the liquid contents of the compartment 44 and of the tube 30 will thus be caused to overflow, and pass outwardly through the outlet 33 until the liquid contained within the compartment 44 reaches the level of the outlet, whereupon no further liquid will be discharged.

It is of course to be understood that the liquid within the compartment 44 always constitutes a seal to prevent the down-flow of liquid from the receptacle 22 while the said receptacle is in its normal position as

shown in Fig. 1 and while it is being swung backwardly to and rests in its tilted position shown in Fig. 4. However, as soon as the predetermined quantity of liquid has been drawn and the receptacle 22 permitted to swing back to its normal position, a portion of the liquid contained within receptacle 22 will flow downwardly to fill the space left vacant within the compartment 44 by the withdrawal of the liquid during the preceding operation. As soon as the level of the liquid contained within compartment 44 reaches the highest portion of the opening 28, the downflow of liquid from receptacle 22 will stop automatically and the foregoing operation can then be repeated.

Obviously by increasing or diminishing the size of the compartment 44 the quantity of liquid discharged at one time can be controlled. This compartment 44 can be enlarged by using additional spacing rings 27. Moreover, by adjusting the loop 16 longitudinally the stop portion 17 thereof can be brought nearer to or farther from the receptacle 22 so as to control the tilting and further regulate the amount of liquid withdrawn from the apparatus at one time.

It will be seen that the apparatus herein described does not require the use of valves or other movable parts necessary to produce the discharge of a portion of the liquid contents of the receptacle, and as a result, the device will not get out of order as a result of long continued use. By making the receptacle 22 of glass or other transparent material the contents thereof can be seen at all times.

Obviously various changes may be made in the construction and arrangement of parts without departing from the spirit or sacrificing the advantages of the invention.

What is claimed is:—

1. In dispensing apparatus a tiltably supported liquid receptacle, an outlet tube open at both ends and communicating at an intermediate point with the bottom thereof, and a sealing compartment interposed between said tube and receptacle and communicating therewith, said compartment opening, adjacent the front thereof, into the receptacle and adjacent the rear thereof into the tube both ends of the tube being normally disposed above the bottom of the receptacle.

2. In dispensing apparatus a tiltably supported liquid receptacle, an outlet tube open at both ends, and a sealing compartment interposed between the tube and the bottom of the receptacle, said compartment communicating adjacent the front thereof with the receptacle and adjacent the rear thereof with the intermediate portion of the tube the open ends of the tube being normally disposed above the bottom of the receptacle.

3. In dispensing apparatus a liquid receptacle bodily tiltable, an outlet tube open at

both ends, and a compartment interposed between the bottom of the receptacle and an intermediate portion of the tube, said compartment having an inlet and an outlet disposed out of alignment, the inlet being normally at a higher elevation than the outlet, said compartment being adapted to trap liquid to control the discharge thereof from the receptacle to the tube the open ends of the tube being normally disposed above the bottom of the receptacle.

4. In dispensing apparatus a tiltable liquid receptacle, an outlet tube open at both ends and extending beyond opposite portions of the receptacle, a compartment for trapping liquid between the receptacle and an intermediate portion of the tube, said compartment having an inlet and an outlet normally located at different elevations and constantly disposed out of alignment; the said compartment being adapted to control the discharge of liquid from the receptacle of the tube the ends of the tube being normally disposed above the bottom of the receptacle.

5. In dispensing apparatus a liquid receptacle having an outlet in the bottom thereof, a tube having open end normally disposed above the bottom of the receptacle, one of said ends constituting a liquid outlet and disposed normally above the outlet of the receptacle, and a compartment for trapping liquid between the intermediate portion of the tube and the outlet to control the discharge of liquid from said outlet to the tube, said compartment having an inlet in the top thereof and an outlet in its bottom, the said inlet and outlet being out of register with each other, said receptacle and tube being bodily shiftable to bring the outlet of the tube below the normal level of the liquid therein.

6. In dispensing apparatus a liquid receptacle having an outlet in the bottom thereof, a tube extending below said receptacle and having open ends disposed at all times below the level of the liquid contained within the receptacle, one of said ends constituting an outlet normally disposed above the outlet of the receptacle, said tube and receptacle being tiltable to bring the outlet of the tube below the normal level of the liquid within the tube, and a compartment for trapping liquid between the tube and the outlet of the receptacle to control the discharge of liquid from the receptacle to the tube, said compartment having an inlet in the top thereof and an outlet in the bottom thereof, said inlet and outlet being out of register with each other.

7. In dispensing apparatus a tiltable liquid receptacle having an outlet in the bottom thereof, a tube extending underneath the outlet of the receptacle and having both of its ends open, one of said ends constituting a liquid outlet constantly disposed above the

- outlet of the receptacle, said tube and receptacle being tiltable together, and a compartment for trapping liquid between the tube and the outlet of the receptacle to control the discharge of liquid from the receptacle to the tube, said compartment having an inlet in the front portion of the top thereof and an outlet in the back portion of the bottom thereof.
- 10 8. In dispensing apparatus a liquid receptacle bodily tiltable, a tube extending under the receptacle and having an outlet in the front thereof, and a sealing compartment interposed between the receptacle and the tube, 5 said compartment communicating at its front end with the receptacle and at its rear end with the tube, the outlet of the tube being disposed at all times in a plane parallel with but extending above the sealing compartment.
- 15 9. In dispensing apparatus a liquid receptacle bodily tiltable, an outlet tube extending under the receptacle and having upturned end portions, a sealing compartment interposed between the tube and receptacle and opening at the front end of its top into the receptacle and at the back end of the bottom thereof into the tube, said inlet and outlet being disposed at all times out of vertical 25 alignment, the tube and compartment coöperating to maintain the level of the liquid within the tube and compartment normally above the outlet of the receptacle.
- 30 10. In dispensing apparatus a bodily tiltable liquid receptacle, an outlet tube thereunder and having upturned ends, and a sealing compartment interposed between the receptacle and tube and communicating at its front end with said receptacle and at its rear end with a tube, said tube and compartment coöperating to maintain the level of the liquid therein above the outlet of the receptacle while said receptacle is in its normal position and while being tilted in 35 one direction.
- 35 11. In dispensing apparatus a bodily tiltable liquid receptacle, an outlet tube thereunder and having upturned ends, and a sealing compartment interposed between the receptacle and tube and communicating at its front end with said receptacle and at its rear end with the tube, said tube and compartment coöperating to maintain the level of the liquid therein above the outlet of the receptacle while said receptacle is in its normal position and while being tilted to 40 discharge liquid from the tube.
- 45 12. In dispensing apparatus a bodily tiltable receptacle, an outlet tube thereunder and having upwardly extending open end portions, a sealing compartment interposed between the tube and receptacle and communicating at diametrically opposed points with the receptacle and tube respectively, 45 said receptacle and tube being tiltable to
- discharge a portion of the contents of the tube, and adjustable means for limiting the tilting movement of the receptacle.
13. In dispensing apparatus a supporting structure, a tiltable liquid receptacle mounted thereon, an outlet tube extending under and detachably connected to the receptacle, means for trapping liquid between the receptacle and tube to control the discharge of liquid from the receptacle to the tube, co-operating means upon the receptacle and supporting structure for holding the receptacle and tube normally in a predetermined position, and adjustable means upon said structure for limiting the tilting movement of the receptacle to discharge the liquid.
14. In dispensing apparatus a supporting structure, a yoke outstanding therefrom, a liquid receptacle pivotally mounted upon and suspended from the yoke, co-operating means upon the yoke and receptacle for holding said receptacle normally in a predetermined position, an outlet tube detachably connected to and extending under the receptacle, means for trapping liquid between the tube and receptacle to control the discharge of liquid from the receptacle to the tube, and adjustable means for limiting the tilting movement of the receptacle and regulating the discharge of fluid from the tube.
15. In dispensing apparatus a bodily tiltable receptacle having an outlet in the bottom thereof, an outlet tube extending under the receptacle and having upwardly extending open end portions, a sealing compartment interposed between the tube and the receptacle and communicating at its front end with the receptacle and at its rear end with the tube, and a refrigerant-holding device detachably mounted within the receptacle and removable therefrom with the tube.
16. In apparatus of the class described a bodily tiltable liquid receptacle, a base plate detachably connected thereto, an outlet tube carried by the plate and having upwardly extending open end portions, there being an aperture in the rear portion of the plate and opening into the tube, a partition mounted upon and spaced from the base plate and having an aperture opening into the front portion of the receptacle, said base plate and partition forming a sealing compartment therebetween.
17. In apparatus of the class described a bodily tiltable liquid receptacle, a base plate detachably connected thereto, an outlet tube carried by the plate and having upwardly extending open end portions, there being an aperture in the rear portion of the plate and opening into the tube, a partition mounted upon and spaced from the base plate and having an aperture opening into the front portion of the receptacle, said base plate

and partition forming a sealing compartment therebetween, a refrigerant-holder detachably mounted within the receptacle, and means extending through the partition for 5 detachably connecting said holder with the base plate.

In testimony that I claim the foregoing

as my own, I have hereto affixed my signature in the presence of two witnesses.

HORACE PFOUTS GORMAN.
